UNITED STATES PATENT OFFICE.

WILLIAM I. DAVIS, OF LITTLE ROCK, ARKANSAS, ASSIGNOR OF ONE-HALF TO EMIL A. VOGEL, OF LITTLE ROCK, ARKANSAS.

FLYING-MACHINE.

1,296,631.

Specification of Letters Patent.

Patented Mar. 11, 1919.

Application filed January 16, 1917. Serial No. 142,691.

To all whom it may concern:

Be it known that I, WILLIAM I. DAVIS, a citizen of the United States, and a resident of Little Rock, in the county of Pulaski and 5 State of Arkansas, have invented a certain new and useful Improvement in Flying-Machines, of which the following is a specification.

The present invention relates to aerial 10 crafts, and particularly to that of the heavier than air type.

It is an object of the present invention to provide an air craft of aeroplane type with 15 elevating means for raising the craft vertically and directly from the ground, and to thus obviate the necessity of the usual launching run along the ground to produce the required pressure of air beneath the supporting plane for lifting the craft, the means 20 being adapted to also sustain the craft substantially at rest at various elevations in the air for observation work, and the like.

Another object of the present invention is to provide the air craft with elevating and 25 sustaining means at each side, and at each end, and to so connect these means that the same will act as a stabilizer for the craft, and maintain it in upright position at all 30 times, and under varying air pressure and load conditions.

The invention still further aims at the provision of a light, safe and easily controlled craft adapted for carrying heavy loads, and being adaptable for passenger, 35 pleasure, freight and observation use, and particularly for use in warfare.

The above, and other objects and advantages of this invention will be brought out more specifically in the following detailed description of the present preferred embodiment, the same being illustrated in the accompanying drawings wherein:

Figure 1 is a perspective view of an aeroplane of the biplane type, the same being 40 constructed in accordance with the present invention.

Fig. 2 is a longitudinal section taken centrally through the craft, the rear end of the same being broken away.

Fig. 3 is a horizontal section of the craft.

Fig. 4 is a detail, enlarged, horizontal sectional view of the gear connection between the elevating devices, the view showing the under side of the same.

Fig. 5 is a bottom plan view of one of the 55 elevating devices.

Fig. 6 is a vertical central section, enlarged, taken through the same.

Fig. 7 is a detail fragmentary view of the lower end of one of the elevating devices, 60 showing the adjustable shutter for controlling the passage of air through the casing of the device.

Fig. 8 is a fragmentary sectional view of the lower end of the casing of one of the 65 raising devices, enlarged, showing the mounting and connection of the louver blinds which comprise the shutters.

Referring to these drawings wherein like parts are designated by similar numerals of 70 reference throughout the several views, the invention is disclosed as being embodied in an aeroplane of the biplane type, wherein the upper and lower supporting planes 10 and 11 are substantially V-shaped, and are 75 secured in vertically spaced-apart relation by means of struts 13. The angled corners of the planes 10 and 11 constitute the forward end of the air craft, and the rear ends of the planes are interbraced and connected together by means of transversely extending 80 brace bars 12. The body of the air craft is therefore given substantially triangular shape, the apex of the triangle constituting the forward end thereof. The usual supporting wheels 14 may be provided upon the three corners of the frame in order to support the same and permit of the easy manipulation of the machine when on the ground. 85

The lower plane 11 is provided with a 90 platform 15 upon which a car or other suitable passenger or freight-carrying device may be mounted, the platform 15 being arranged intermediate the ends of the body, and the rear end of the body being provided 95 with a base or platform 16 upon which a suitable engine or motor 17 may be mounted for driving the craft. The brace bars 12 at the rear end of the body are provided, in the usual manner, with a pair of propellers 18 which are connected by a chain 19, or the like, to the motor 17. If desired, a clutch 19^a may be interposed between the motor 17 and the propellers 18 for disengaging the latter from the motor and permitting the 100 motor to run independently of the propellers. 105

A vertical shaft 20 is mounted in the body

forwardly of the motor 17, and is connected thereto by bevel gears 21, or the like. The shaft 20 is provided with a large bevel gear 22, with which mesh a plurality of pinions 23 which are mounted upon shafts 24 which extend toward the corners of the body and are geared, as at 25, to elevator shafts 26. Clutches 27 are interposed in each shaft 24 and have connection by means of rods 28 10 with hand levers 29 mounted upon a platform 30 arranged over the motor 17.

Each elevating device comprises a pair of conical sections or casings 31 which are relatively short, and flare abruptly from top to 15 bottom. The enlarged base ends of the casings 31 open downwardly through the top and bottom planes 10 and 11, and are arranged in vertical registry for receiving the opposite ends of the shaft 26. Each shaft 26 20 is journaled at its opposite ends in bearings 32 which are arranged within the casings 31. Each casing 31 is provided with a spirally-formed propeller 33 which corresponds to the upwardly tapering formation of the casing, and which is adapted to fit snugly therein. The lower ends of the casing 31 are closed by a plurality of transversely pivoted shutters or louver blinds connected at their lower edges to an operating rod 34. The 25 blinds, indicated at 35, are adapted to overlap when swung into substantially horizontal position and to thus close the passage upwardly through the casing 31. The rods 34 of each pair of elevators are connected by 30 means of branch rods 36, to a handle 37 arranged adjacent to the platform 15 and adapted to be moved horizontally to shift the shutters 35.

The craft is provided, in the usual manner, 40 with the horizontally disposed tiltable planes or rudders 38 which are carried horizontally at the rear end of the craft for deflecting the latter into various horizontal planes. The craft is also provided with a 45 vertically disposed rudder 39 which is located in the usual manner intermediate the lateral edges of the planes 38 and which is adapted to be swung into various positions for controlling the lateral movements of the 50 craft.

In operation, when it is desired to raise the craft into the air, it is only necessary to operate the shaft 20 by the motor 17, and to adjust the clutches 27 for driving the shafts 24. The turning of the shafts 24 rotates the vertically disposed elevating shafts 26, and the latter turn the spirally-formed propellers 33 in each of the casings 31. The gears are so arranged that the blades 33 are turned 60 in a direction to force a draft of air downwardly through the casings 31, thus creating an air-pressure beneath the planes 10 and 11, and effecting the vertical recoil of the air craft. The provision of the casings 31 65 forms a means for providing a direct strong

current of air downwardly, and as this current of air is produced at each corner of the machine, the latter is raised uniformly at both ends and at both sides. This action of the propeller 33 may be regulated not only 70 by the speed of the motor 17, but also by the adjustment of the shutters 35.

After the desired height has been attained, the clutch 19^a may be thrown into operation so as to drive the propellers 18 75 and thus convey the craft horizontally through the air. At this time, the elevators may be disconnected from the motor 17, and the shutters 35 closed so that the device may glide through the air in the usual manner of 80 aeroplanes, the casings 31 serving as air bells or pockets to receive a large volume of air therein for equalizing or stabilizing the craft during its gliding movement.

Should the motor 17 become inoperative 85 while in flight, the clutches 27 and 19 may be adjusted to interlock the elevating propellers 33 with the propellers 18. The falling of the body at this time produces upward currents of air under considerable 90 pressure through the casings 31, and when the blinds 35 are open, the propellers 33 are driven at a rapid rate of speed so as to drive the shafts 24 and operate the propellers 18 through the engine or motor 17 as the connection. Thus a certain gliding movement will be given to the body during its descent and a safe landing may be made, the machine being under control of the operator to a great extent. When the propellers 18 95 are operated by the rotation of the propellers 33, the lever 21^a is operated to shift the gear 21' into the vertical miter gear 21, to rotate the propellers 18 in the same direction in which they are rotated by the operation of the engine and to impart a forward 100 gliding movement to the flying machine.

Stabilization may be effected by relieving the air pressure beneath the elevated portion of the craft. This is accomplished by 110 opening when the blades 33 are stationary, to a more or less extent, the shutters 35 of the raised cone casing, and permitting the air to pass upwardly against the larger lower end of the blade 33. The air is compressed into the reduced upper end of the casing, is impacted against the smaller end of the blade 33, and is finally discharged through the reduced upper open end of the casing in a whirling reduced stream.

It is of course understood that various changes and modifications may be made in the details of construction of the above-specified air craft without departing from the spirit of the invention, this 125 being restricted only by the scope of the following claims.

I claim:

1. In an air craft, the combination of a bi-plane provided with the usual propelling 130

- means, of pairs of vertically alined elevating propellers one of which is arranged in each plane of said biplane, and means for driving each pair of propellers as a unit.
5. 2. In an air craft, the combination of a biplane, vertically alining open-ended casings opening through the opposite ends and sides of the planes of said biplane, spiral blades mounted in the castings, and means 10 for turning said blades simultaneously to create vertical currents of air through said planes at the opposite sides and ends thereof.
3. In an air craft, the combination of a biplane, vertical open-ended casings opening 15 through the opposite ends and sides of the planes of said biplane, air current creating propellers arranged in said casings, and means for simultaneously driving all of said propellers to equalize the air pressure beneath the opposite ends and sides of the 20 planes and to compensate for variations in loads and pressure therebeneath.
4. In an air craft, the combination of a biplane, of a plurality of vertically alining open-ended casings opening through the opposite ends and sides of the planes of said biplane, air current creating propellers arranged in said casings, means for driving said propellers to elevate and sustain said 30 planes in the air, and adjustable shutters carried by said casings for controlling the air current therethrough.
5. In an air craft, the combination of a pair of vertically spaced-apart planes substantially triangular in shape, an elevating device arranged at each corner of the planes, and means connecting said elevating devices to actuate the same simultaneously for 35 equalizing the pressure beneath each corner 40 of each plane.
6. In an air craft, the combination of a body comprising vertically-spaced-apart triangular frames, an elevating device at each corner of each frame, means connecting the adjacent elevating devices together, and means for simultaneously operating all of 45 said elevating devices to drive the same as a unit and to equalize the air pressure at the opposite ends and opposite sides of the body.
50. 7. In an air craft, the combination of a biplane provided with the usual propelling means, of pairs of vertically alined elevating propellers one of which is arranged in each plane of the biplane, open ended upwardly 55 tapering casings surrounding said propellers, and adjustable means positioned at the lower ends of said casings for regulating the quantity of air passing therethrough.
8. In an air craft, the combination of a 60 biplane provided with the usual propelling means, of pairs of vertically alined elevating propellers one of each pair of which is arranged in each plane of the biplane, means for simultaneously guiding all of said propellers to equalize the air pressure beneath 65
- the opposite ends and sides of the planes and to compensate for variations in loads and pressure therebeneath, and means controlling the driving of said propellers whereby any alining pair may be driven independently of the other propellers. 70
9. In an air craft, the combination, of a pair of vertically spaced apart planes substantially triangular in shape, pairs of vertically alined elevating propellers arranged 75 at each corner of the planes, one of each pair of which is carried by each plane of the biplane, means for simultaneously driving all of said propellers to equalize the air pressure beneath the opposite ends and sides of the 80 planes and to compensate for variations in loads and pressure therebeneath.
10. In an air craft, the combination, of a pair of vertically spaced apart planes substantially triangular in shape, pairs of vertically alined elevating propellers arranged 85 at each corner of the planes, one of each pair of which is carried by each plane of the biplane, means for simultaneously driving all of said propellers to equalize the air pressure 90 beneath the opposite ends and sides of the planes and to compensate for variations in loads and pressure therebeneath, and means controlling the driving of said propellers whereby any alining pair may be 95 driven independently of the other propellers.
11. In an air craft, the combination, of a pair of vertically spaced apart planes substantially triangular in shape, pairs of vertically alined elevating propellers arranged at 100 each corner of the planes, one of each pair of which is carried by each plane of the biplane, means for simultaneously driving all of said propellers to equalize the air pressure beneath the opposite ends and sides of the 105 planes and to compensate for variations in loads and pressure therebeneath, means controlling the driving of said propellers whereby any alining pair may be driven independently of the other propellers, open ended upwardly tapering casings surrounding said propellers, and adjustable means positioned at the lower ends of said casings for regulating the quantity of air from passing therethrough. 110
12. In an air craft, the combination, of a pair of vertically spaced apart planes substantially triangular in shape, vertical open ended upwardly tapering casings arranged at each corner of the planes in alining pairs, spiral bladed propellers rotatable within said casings and means connecting said spiral propellers to rotate them simultaneously for equalizing the pressure beneath each corner of each plane. 115
13. In an air craft, the combination, of a pair of vertically spaced apart planes substantially triangular in shape, vertical open ended upwardly tapering casings arranged at each corner of the planes in alining pairs, 120
- 130

spiral bladed propellers rotatable within said casings and means connecting said spiral propellers to rotate them simultaneously for equalizing the pressure beneath each corner of each plane, and means for controlling the rotation of said propellers whereby any alining pair may be driven independently of the other propellers.

14. In an air craft, the combination, of a pair of vertically spaced apart planes substantially triangular in shape, vertical open ended upwardly tapering casings arranged at each corner of the planes in alining pairs,

spiral bladed propellers rotatable within said casings and means connecting said spiral propellers to rotate them simultaneously for equalizing the pressure beneath each corner of each plane, means for controlling the rotation of said propellers whereby any alining pair may be driven independently of the other propellers, and louver blinds positioned at the lower ends of said casings for regulating the quantity of air passing therethrough.

WILLIAM I. DAVIS.
